CLAIM

The ornamental design for an illuminated sign, as shown and described.

DESCRIPTION

FIG. 1 is a front elevation view of an illuminated sign showing the new design.

FIG. 2 is a top plan view and a bottom plan view respectively thereof.

FIG. 3 is a right end view, the left end view is identical thereto. The broken lines shown are for illustrative purposes only and form no part of the claimed design.

FIG. 4 is a front elevation view of the illuminated sign shown in an alternate position of use.

FIG. 5 is a right end view thereof.

FIG. 6 is a left end view thereof.

FIG. 7 is a rear elevation view thereof.

FIG. 8 is a top plan view thereof; and,

FIG. 9 is a bottom view thereof.

The broken lines shown are for illustrative purposes only and form no part of the claimed design.
